UNITED STATES PATENT OFFICE

2,243,651

WATER HEATER

Henry C. Price, Elizabeth City, N. C.

Application September 11, 1939, Serial No. 294,362

1 Claim. (Cl. 219—40)

The present invention relates to water heaters embodying a vessel having a pair of electrical terminals positioned in the bottom thereof for immersion in the liquid contained within the vessel whereby to form a conductor for the current passing through said terminals to heat the water.

An object of the present invention is to provide a device of this character designed particularly for use in heating a small quantity of water for shaving and which embodies simplicity of construction, which is efficient and reliable in performance, relatively inexpensive to manufacture and otherwise well adapted for the purposes for which the same is intended.

Other objects and advantages reside in the details of construction as more fully hereinafter described and claimed, reference being had to the accompanying drawing forming part hereof, wherein like numerals refer to like parts throughout, and in which—

Figure 1 is a vertical sectional view, and
Figure 2 is a top plan view.

Referring now to the drawing in detail, wherein for the purpose of illustration I have disclosed a preferred embodiment of the invention, the numeral 5 designates an open receptacle, preferably of insulation material and having a recess 6 in the surface of its bottom portion 7. Positioned in the recess is a pair of electrical conductors indicated at 8 and 9, both of said conductors being of annular form, the conductor 8 being of relatively smaller diameter and including a ring portion 10 positioned upright in the recess and having its upper edge formed with an outwardly extending flange 11.

The conductor 9 is likewise in the form of a ring which surrounds the ring portion 10 of the conductor 8 and is spaced outwardly therefrom. The upper edge of the ring 9 terminates in spaced relation beneath the flange 11.

The bottom edge of the ring portion 10 of the conductor 8 is formed with a horizontally extending lug 12 while the bottom edge of the

conductor 9 is likewise formed with a horizontally extending lug 13.

Each of the lugs 12 and 13 are formed with openings for receiving electric terminals 14 and 15, respectively, said terminals extending through the bottom 7 of the receptacle, and are suitably secured in position by means of nuts 16 or the like. The lower ends of the terminals 14 and 15 have electric wires 17 and 18, respectively, connected thereto, which extend through an opening 19 formed in one of the side walls 20 of a supporting base 21, said base supporting the receptacle in an elevated position and includes an inturned flange 22 secured to the bottom of the receptacle by screws or the like 23.

The receptacle 5 may be constructed of octagonal shape as shown in Figure 2 of the drawing, or constructed of any other desired shape.

From the foregoing it will be apparent that when liquid, as indicated at 24, is placed within the vessel, the same will act as a conductor between the conductors 8 and 9, the electric current passing through said conductors serving to heat the water or other liquid.

It is believed the details of construction and manner of use of the device will be readily understood from the foregoing without further detailed explanation.

Having thus described the invention, what I claim is:

An electric heater comprising a receptacle of insulation material having a well formed in the surface of its bottom portion, a pair of electric conductors positioned in said well, each of said conductors embodying inner and outer concentrically arranged spaced rings, the outer ring being spaced from the wall of the well, one of said conductors also embodying a horizontal flange overlying and spaced from the other conductor, said flange having its surface in the horizontal plane of the surface of the bottom of the receptacle, lugs on said conductors and electric terminals extending through the bottom of the receptacle and attached to said lugs.

HENRY C. PRICE.
